(57) **CLAIM**

The ornamental design for an RF wireless modem, as shown and described.

DESCRIPTION

FIG. 1 is a front perspective view of an RF wireless modem according to the present invention;

FIG. 2 is a front view of an RF wireless modem according to the present invention;

FIG. 3 is a back view thereof;

FIG. 4 is a top view thereof;

FIG. 5 is a bottom view thereof;

FIG. 6 is a right side view thereof; and,

FIG. 7 is a left side view thereof.
